(57) CLAIM

The ornamental design for a floor mat, as shown and described.

DESCRIPTION

FIG. 1 is a top front perspective view of a floor mat;

FIG. 2 is a front elevation view thereof;

FIG. 3 is a top elevation view thereof;

FIG. 4 is a bottom elevation view thereof;

FIG. 5 is a rear elevation view thereof;

FIG. 6 is a right side elevation view thereof; and,

FIG. 7 is a left side elevation view thereof.

The broken lines shown in the drawings depict portions of the floor mat that forms no part of the claimed invention.

1 Claim, 3 Drawing Sheets
